UNITED STATES PATENT OFFICE.

JOHN H. COOK, OF NEW YORK, N. Y., ASSIGNOR TO HENRY B. NEWHALL,
OF PLAINFIELD, NEW JERSEY.

TROLLEY TRACK AND LIFT MECHANISM.

SPECIFICATION forming part of Letters Patent No. 630,798, dated August 8, 1899.

Application filed December 13, 1897. Renewed February 18, 1899. Serial No. 706,064. (No model.)

To all whom it may concern:

Be it known that I, JOHN H. COOK, a citizen of the United States, residing at New York, (Brooklyn,) in the county of Kings and State 5 of New York, have invented a certain new and useful Improvement in Trolley Track and Lift Mechanism, of which the following is a specification, reference being had to the drawings accompanying and forming a part 10 of the same.

The present invention relates to a trolley-track mechanism combined with a lift, carrier, or elevator mechanism, the general arrangement of the two mechanisms being such 15 that a section of the trolley-track is removable from the main portions of the track, being carried on the lift mechanism, which is operated to cause said section to engage or register with the portions of the main track 20 and to be moved laterally therefrom or to another level.

As an example of one form of mechanism embodying my invention I have illustrated and shall herein describe what is known as a 25 "trolley" ash-lift mechanism, which consists in general of a trolley line or rail system extending horizontally underground, as from boilers or furnaces of a building to underneath the pavements on one side of the same, at 30 which latter point a section of the trolley-track is removable from the main track and is attached to a vertically-moving lift or carrier, whereby an ash-receptacle can be run from the boilers to the pavement and while 35 hanging on said removable section be lifted to the ground-level or to just above pavement and then run off said section to be deposited on the pavement, or, if desired, run onto another trolley-rail for conducting the receptacle elsewhere.

Referring to the drawings, Figure 1 shows a front elevation view of the lift mechanism. Fig. 2 is a side elevation of the same, the lift being in central vertical section. Fig. 3 shows 45 a front elevation of the lift or trolley mechanism; and Fig. 4, a side view of the same, the vertical tubular track inclosing the same being partially sectioned away.

Referring to the views in detail, A represents the ground-level or the upper face of a

pavement surrounding a building, the walls of which are indicated by B, and C represents the upper or pavement opening of a lift-shaft, while D represents a horizontal underground passage extending to a place to or from which 55 it is desired to carry ashes, coal, or other material. Secured to the upper walls of said passage is the trolley-track E, which may be of any suitable construction, although shown as of tubular form. F is the removable section of this track, which is supported in the hanger-shoes G, which are shaped to guide and hold this section in line with the main track and registering with its ends H, but which permit said section to be (in this case) 60 raised vertically from the main portions of the track.

I represents an elevator or elevator-frame, which is shown as constructed of bar-iron and has fastened to its upper cross-bar J the 70 said section of track F. This lift-frame is provided with four trolleys K, two on each side, which run in the vertically-arranged tubular trolley-tracks L, said tracks being secured by brackets M to the upright post N. 75 The two upper trolleys are attached to chains O, which pass around sheaves P at the bottom of the underground passage and run to the winding-drum Q of the hand-operated winch mechanism R, which mechanism is for 80 the purpose of raising and lowering the lift.

S represents a can which may be used for conveying ashes, coal, or the like. The bail T of this can is hung to the hook U of the trolley mechanism V, which latter mechanism 85 may be of any suitable construction adapted to run on the trolley-tracks E and F.

The trolley mechanism K is composed of two pairs of trolley-rolls W and W' and X and X', the rolls of each pair being arranged 90 at right angles to each other and one pair being secured to each end of the connecting-bar Y, which is attached to the lower cross-bar Z of the elevator, so that one pair of rolls is above said cross-bar and the other pair 95 below the same. This arrangement is important to steady the elevator as it rises and lowers and to prevent the binding of the trolleys in the vertical trolley-tracks, as the elevator, when loaded, is likely to sway in 100

various directions. Furthermore, the use of such trolleys permits me to locate the same at the lower end of the elevator, leaving the upper and loaded end unsupported and unguided, so that such upper end may be projected from the lift-shaft to a sufficient height for removing the can, thus avoiding the use of any other supporting or guiding mechanism above the pavement or ground-level and minimizing the obstruction of the pavement at the time the elevator is raised and the can is being moved, as also permitting the easy and quick closing of the pavement-opening of the lift-shaft.

15 The operation of the mechanism will now be plain. Assuming that the can has been loaded with ashes, coal, or whatever it may be desired to remove, the can will be propelled along the main track until its trolley runs on 20 the removable section, it being assumed that the elevator is at the lower end of its shaft. After the can has been run on the removable section of the track carried by the lift the lift may be raised and the can brought to 25 position, as shown in Fig. 2, whereupon it may be run along the track F to over and deposited on the pavement, or, if desired, run upon another track (shown by dotted lines in Fig 2) for conveying it from the elevator-shaft. Of course it will be understood that 30 the same mechanism may be utilized for conveying loads from the ground-level to the underground track, as in the case of storing coal, and similarly this mechanism may be used for conveying from one level to another 35 various other materials or supplies, the description and illustrations herein being in-

tended to represent a type of mechanism embodying the invention.

What is claimed as new is—

1. In combination in a trolley lift mechanism and for the purpose set forth, a lift or elevator, vertical tubular tracks as L, and four or more trolleys as K connecting the lower end of said lift with said tracks, whereby 45 the upper loaded end of the lift can be projected beyond the upper end of the tracks, for the purpose set forth.

2. In combination in a trolley lift mechanism, vertical tubular tracks as L, and four or 50 more trolleys as K connecting the lower end of said lift with said tracks for the purpose set forth, and lifting mechanism such as chains O and the winch R, substantially as set forth.

3. The combination with a vertically-moving lift and in a trolley mechanism for guiding the same, of a vertically-arranged tubular track, and a pair of trolley-wheels engaging the track and attached to the lift and arranged at right angles to each other, substantially as set forth.

4. In combination in a trolley mechanism for guiding a vertically-moving lift, a tubular rail vertically arranged, and two pairs of 65 trolley-rolls, the rolls of each pair being arranged at right angles to each other, a bar connecting the pairs of rolls, and means of attachment to a lift fixed to said bar between said pairs of rolls, substantially as set forth. 70

JOHN H. COOK.
